MINE CAR

Filed Oct. 5, 1928

UNITED STATES PATENT OFFICE

LEOPOLD ALMQUIST, OF JERSEY CITY, NEW JERSEY, ASSIGNOR TO AMERICAN CAR AND FOUNDRY COMPANY, OF NEW YORK, N. Y., A CORPORATION OF NEW JERSEY

MINE CAR

Application filed October 5, 1928. Serial No. 310,656.

This invention relates to drop bottom mine cars of the type in which one door automatically operates the latch of a second door to release or lock the second door as the first door is lowered or raised and it is an object of this invention to provide improved means for hinging and locking doors of mine cars of the type described which will be of simple and rugged construction, of few parts readily applied, reliable in operation and easily maintained in serviceable condition where extensive repair shops are not available.

Other objects and advantages of this invention will be apparent from the following description, taken in conjunction with the accompanying drawings, in which:

Figure 1 is a fragmentary vertical longitudinal section taken at one of the axles of the car and showing the door hinging and latching means, the doors being in closed position;

Fig. 2 is a section taken on the line 2—2 of Fig. 1, parts being broken away to show other parts more clearly;

Fig. 3 is a view similar to Fig. 1, the doors being shown in the open position;

Fig. 4 is a perspective view of the latch operating cam shown detached;

Fig. 5 is a fragmentary section showing a modified form of the latch operating cam in engagement with the latch;

Fig. 6 is a section taken on the line 6—6 of Fig. 5; and

Fig. 7 is a view similar to Fig. 2 of a modified construction.

The drawings show a fragment of a mine car having sills 1 through which extend axles 2 having wheels (not shown) thereon. The axles are journaled in boxes 3 secured to the side sills. To the sills 1 are attached hinge brackets 4 having openings to receive the axles 2 and outwardly extending ribs or flanges 6 which extend around the axle openings and the lower portions of which are bifurcated, forming spaced arms 8. The arms

8 are formed with aligned circular bearing openings in which are journaled bushings 10 having rectangular openings. Fitting the openings in the bushings 10 are rectangular hinge pins 12 which fit correspondingly-shaped openings in the hinge straps 14 attached to the dumping doors 16, the hinge straps 14 being inserted between the arms 8 of the hinge brackets 4. The hinge pins 12 project beyond the arms 8 of the hinge brackets 4 and have mounted thereon cams 30 formed with the rectangular slots 32 which fit the hinge pins 12. Journaled on the axles 2 by means of hinge straps 18 are latches 20 comprising angle plates 22 extending substantially from sill to sill and braced by the flanged braces 24 where they are connected to the hinge straps 18. Projecting laterally from the flanges 26 of the braces 24 are arcuate ribs 28.

In assembling this construction, the latch 20 is journaled on the axle 2, the hinge straps 14 are placed between the arms 8 of the hinge brackets, and the hinge pins 12 are inserted in the openings in the bushings 10 and hinge straps 14 through an opening 34 provided in the flange 26 of the brace 24. As the pins 12 are inserted in the openings in the bushings 10 and hinge straps 14 they are engaged in the slots 32 of the cams 30 held between the hinge brackets 4 and the braces 24 in position to engage with the ribs 28 on the flanges 26 of the braces 24, the rib 28 retaining the cam 30 on the pin 12. Movement of the pin outwardly is prevented by engagement of the pin with the sill 1, while movement of the pin in the opposite direction is prevented by a cotter 36 inserted in an opening in the pin.

To the upper portion of the ribs 6 there are secured braces 38 which conform to the shape of the ribs and unite the ribs of opposite hinge brackets. The braces 38 are provided with outwardly projecting flanges 40 and 42 which extend over the inner edges of the

50

90

doors hinged to the adjacent brackets and over the latches mounted on the adjacent axles and the free edges of the doors supported by the latches so that the braces 38 form shields for the latches.

5 In the modification shown in Figs. 5 and 6, the cam 30' is provided with bosses 60 formed on either side thereof. The bosses 60 have rectangular openings therein to fit the rectangular hinge pin 12'. The hinge pin 12' extends beyond the cam 30' and into an elongated opening 34' formed in the flange 26' of brace 24' to allow full movement of the latch 20. The extended end of hinge pin 12' is provided with an opening 61 for insertion of a cotter if desired. Brace 24' is recessed at 10 15 62 to clear the bosses 60.

In the modification shown in Fig. 7 the hinge bracket 4' is provided with a rib 6' which forms but a single arm provided with a circular bearing recess 46. In this construction, the hinge strap 14' is formed with a trunnion 48 and a cam 50 integral therewith; the trunnion 48 engaging in the bearing recess 46 while the cam 50 engages in the slot formed by the rib 28. In assembling this construction, the hinge strap 14' is mounted in the bearing recess 46 before the door 16 is secured thereto.

In both constructions, the operation of the door 16 is controlled by any desired means, as, for instance, a suitable latching mechanism operated by a track ramp. When the door 16 is released and drops, the cam 30 or 35 50 is operated thereby and through its engagement with the rib 28 withdraws the latch 20 from beneath the free end of the door 52 permitting the door to drop. The door restoring device will restore the door 52 to its 40 raised position before the door 16 is raised, and when the door 16 is raised the cam 30 or 50 will operate the latch 20 to its door holding position. Restoring the door 16 to its raised position will bring the door into engagement with its retaining latch.

45 The drawings disclose the preferred embodiment of the invention, but it is to be understood that they are for illustrative purposes only, and that various changes in the 50 form and proportions of the device may be made within the scope of the appended claims without departing from the spirit of the invention.

What is claimed is:

55 1. In a mine car, a drop door pivotally mounted on the car, a latch for holding said door in closed position, a second drop door, a hinge for attaching said second door to the car comprising a rectangular hinge pin and a cam having an open-ended slot receiving said hinge pin and operated by said hinge pin to operate said latch.

2. In a mine car, a drop door pivotally mounted on the car, a latch for holding said door in closed position, a second drop door,

a hinge strap having rectangular openings attached to said door, a hinge bracket attached to said car, a rectangular hinge pin fitting the openings in said strap and journaled in said bracket and a cam having an open-ended slot receiving said hinge pin and operated by said hinge pin to operate said latch. 70

3. In a mine car, a drop door pivotally mounted on the car, a latch for holding said door in closed position, a second drop door, a hinge strap attached to said second door, a hinge bracket attached to said car, a rectangular hinge pin fitted in said strap and journaled in said bracket for attaching said second door to the car and a cam having an open-ended slot fitting said hinge pin and operated by said hinge pin to operate said latch.

4. In a mine car, a drop door pivotally mounted on the car, a latch for holding said door in closed position, a second drop door, a hinge strap attached to said second door and having a rectangular hinge pin opening, a hinge bracket attached to the car and having circular openings therein, bushings having rectangular openings journaled in said hinge bracket, a rectangular hinge pin mounted in said hinge strap and bushings and connecting said second door to the car and a cam detachably mounted on said hinge pin for operating said latch. 95

5. In a mine car, a drop door pivotally mounted on the car, a latch extending from side to side of said door for holding said door in closed position, a second drop door and a cam operating with said second drop door to operate said latch to release and locking positions, said latch holding said cam in operative relation to said second drop door. 105

6. In a mine car, a drop door pivotally mounted on the car, a latch extending across said door for holding said door in closed position, said latch having an open-ended slot therein, a second drop door and a cam operating with said second drop door and engaging in said slot to operate said latch to release and locking positions, said latch holding said cam in operative relation to said second drop door. 110 115

7. In a mine car, a drop door pivotally mounted on the car, a latch engaging the free edge of said door for holding said door in closed position, said latch having open-ended slots therein, a second drop door, hinges pivotally connecting said second door to the car and cams operated by said hinges and engaging in said slots to operate said latch to release and locking positions, said latch holding said cams in operative relation to said hinges. 120 125

8. In a mine car, a drop door pivotally mounted on the car, a latch pivotally mounted on the car and engaging the free edge of said door for holding said door in closed position, said latch having open-ended slots 130

therein, a second drop door, hinge straps attached to said door and having angular openings therein, hinge brackets attached to the car and having circular openings therein, bushings having angular openings journaled in the openings in said hinge brackets, angular hinge pins fitting the openings in said hinge straps and bushings and connecting said second door to the car and cams having open-ended slots therein fitted on said hinge pin and engaging in the slots in said latch, said cams operating said latch to release and locking position upon operation of said second door.

9. In a mine car, a drop door pivotally mounted on the car, a latch for said door, said latch having a rib forming an open-ended slot, a second drop door, and a hinge for attaching said second door to the car, said hinge having a cam operatively engaging in the slot formed by said rib to operate said latch, said latch holding said cam in operative relation to said hinge.

10. In a mine car, a drop door pivotally mounted on the car, a latch for said door, said latch having a laterally projecting flange of arcuate form, a second drop door, and a hinge for attaching said second door to the car, said hinge having a cam engaging said flange to operate said latch, said latch holding said cam in operative relation to said hinge.

11. In a mine car, a drop door pivotally mounted on the car, a latch for said door, said latch having a brace provided with a laterally projecting arcuate flange forming an open-ended slot, a second drop door, and a hinge for attaching said second door to the car, said hinge having a cam engaging in the slot formed by the said flange to operate the said latch, said latch holding said cam in operative relation to said hinge.

12. In a mine car, a drop door pivotally mounted on the car, a latch for holding said door in closed position, a second drop door, and a hinge for attaching said second door to the car comprising a hinge pin and a cam detachably mounted on said hinge pin and operated by said hinge pin to operate said latch.

13. In a mine car, a drop door pivotally mounted on the car, a latch pivotally mounted on the car and engaging the free edge of said door for holding said door in closed position, said latch having open-ended slots therein, a second drop door, hinge straps attached to said second door, hinge brackets attached to the car and having bearings for supporting said hinge straps, and cams operating with said hinge straps and engaging in said slots to operate said latch, said latch holding said cams in operative relation to said hinges.

14. In a mine car, a drop door pivotally mounted on the car, a latch pivotally mounted on the car and engaging the free edge of said door for holding said door in closed po-

sition, braces for said latch having laterally projecting arcuate flanges forming open-ended slots, a second drop door, hinge straps attached to said second door, hinge brackets attached to the car and having bearings for supporting said hinge straps, and cams operating with said hinge straps and engaging in said slots to operate said latch, said latch holding said cams in operative relation to said hinges.

In witness whereof I have hereunto set my hand.

LEOPOLD ALMQUIST.
